UNITED STATES PATENT OFFICE.

HARRISON CADY, OF BROOKLYN, NEW YORK, ASSIGNOR TO THORNTON W. BURGESS,
OF SPRINGFIELD, MASSACHUSETTS.

DESIGN FOR AN ARTICLE OF MANUFACTURE.

50,234.

Specification for Design.

Patented Jan. 30, 1917.

Application filed May 6, 1916. Serial No. 95,974. Term of patent 7 years.

To all whom it may concern:

Be it known that I, HARRISON CADY, a citizen of the United States, and resident of Brooklyn, in the county of Kings, city and State of New York, have invented a new, original, and ornamental Design for an Article of Manufacture, of which the following is a specification, reference being had to the accompanying drawings, forming a part thereof.

In the drawings I have shown a representation of a toy embodying my design.

The design as shown comprises an ornamental figure in the form of a fanciful representation of a bear embodied in a toy, but I contemplate that the same may also be embodied in or applied to various other articles of manufacture.

I claim:

The ornamental design for an article of manufacture, as shown and described.

HARRISON CADY.
